UNITED STATES PATENT OFFICE.

JAMES A. THATCHER, OF MATTOON, ILLINOIS.

APPARATUS FOR CLOSING SWITCHES.

SPECIFICATION forming part of Letters Patent No. 501,382, dated July 11, 1893.

Application filed March 11, 1893. Serial No. 465,507. (No model.)

To all whom it may concern:

Be it known that I, JAMES A. THATCHER, a citizen of the United States, residing at Mattoon, in the county of Coles and State of Illinois, have invented certain new and useful Improvements in Apparatus for Closing Switches to be Operated by Moving Trains; and I do hereby declare the following to be a full, clear, and exact description of the invention, such as will enable others skilled in the art to which it appertains to make and use the same.

My invention relates to railroad switches, and it consists in a certain novel device, whereby the switch is closed upon the approach of a train.

The object of my invention is to prevent accidents from open switches which oftentimes are occasioned by the inattention or neglect of the switchman.

Reference is had to the accompanying drawings, in which the same parts are indicated by the same letters throughout the several views.

Figure 1 represents a sectional elevation of the apparatus and illustrates its operation. Fig. 2 represents a plan view of the switch and its connections. Fig. 3 represents a side elevation of the switch-stand and its connections. Fig. 4 represents a view from the opposite side of the switch-stand as shown in Fig. 3, and illustrates the connection of the switch lever to the semaphore. Fig. 5 represents a section along the line $x-x$ of Figs. 3 and 4.

A represents the cowcatcher of the locomotive, which is provided at one side, with a stud or roller a , adapted to strike the projecting arm b of the lever B which is pivoted at b' , and is connected by straps c to the two spring plungers C having springs c' . The function of these springs is to hold the lever B in a vertical position except when the said lever is pressed to one side by the tripping device a attached to the train. These spring plungers C are held in guides D attached to the box D , in which the various parts adjacent to B are preferably mounted. This box is represented as sunk in the ground, at one end of the cross ties, but it may be secured on the top of the ground, and the tripping de-

vice a would, in that case be placed higher up on the locomotive, or on any part of the moving train. To the opposite part of this lever, from the projecting arm b , a rod E is pivotally connected. This rod leads directly to the dog N supporting the switch bar H , as will be hereinafter described. The said switch-lever H is provided with a sliding weight H' and clamp-screw h for holding the said weight at any desired position on the said lever. The lever H is rigidly attached to the disk K which is pivoted in the switch-stand F by a bolt through either the hole f or the hole f' . In Fig. 3 the disk K is represented as pivoted about a bolt k' in the hole f' , and the switch-lever H acts as a pushing lever, to push the switch rail S away from the rail R ; while if the disk K were pivoted in the hole f , and the pin for the connection S' were pivoted in the hole f' , the switch-lever H would act as a pulling lever, and in this way the disk K is adapted to make a reversible connection with the switch rail S . The switch lever H is connected by means of the rod l to the semaphore L mounted on the mast M and operated in the usual way. The switch lever H , when the switch is open, rests on the bevel face n^o of the dog N , as shown in Fig. 4. This dog N is pivoted at n , and has connected thereto by means of eye-bolts n' and n^2 , the rod E , leading to the releasing lever B , and the rod E' , leading to a similar releasing lever at the same distance the other side of the switch as the releasing lever B . This duplication of parts is not shown in the drawings, other than by the rod E' . The dog N has a sloping face n^3 adapted to engage the switch-lever H , which presses the upper arm of the dog back against the spring N' , and allows the switch-bar to pass over the dog; as soon as the pressure of the switch-lever on the cam face n^3 is relieved, as by the passage of the lever H above the dog, the spring N' throws the dog beneath the lever, and prevents the same from falling, as indicated by dotted lines in Fig. 5.

In order that the switch bar may be released at the switch-stand, and allowed to fall, when in the position indicated by the dotted lines in Fig. 5, a pedal N^2 pivoted at

n^6 and having arms n^4 and n^5 , is provided. A spring N^3 may also be provided to normally hold the pedal clear of the dog N , but this is not necessary.

5. By having two releasing levers B one on each side of the switch, and at the requisite distance therefrom, the switch may be closed by a train approaching from either direction, no matter whether left open by the switch-
10 man or not.

The operation of the device is as follows:— The releasing lever B being placed at the required distance from the switch, as the train approaches the roller a strikes the projecting 15 arm b of the releasing lever, bending it down, and at the same time pulling on the rod E which withdraws the dog N from beneath the switch lever arm, and allows the weight H' to drop, closing the switch S . Should the 20 switch be already closed, the dog N will simply be pulled back without occasioning any damage. By arranging the rods E and E' as shown in Fig. 5, the dog N may be moved by 25 trains approaching from either side of the switch, without in any way interfering with the operation of the switch-lever.

In order that there may be a firm yet yielding connection between the disk K and the switch rail S , I preferably construct the connecting rod in two parts S' and S^2 , joined together by a bolt s' having a slight play in the guides s^2 and s^3 and having a head s^4 adapted to bring up against the lug or guide s^5 . The first part of the motion of the weighted arm 35 is taken up by the springs interposed between the two parts of the connecting rod. In this way sudden jerks on the switch are avoided.

It will be obvious that the lug or roller 40 may be placed upon the steps or upon any other portion of the cab, the tender, or the cars of the train, and that it may be mounted on a lever or be otherwise placed under the control of the engineer; that the rods E may 45 be connected to the releasing lever B above the pivot b' , and thus extend above the ground, and that many other modifications might be made, which could be used without departing from the spirit of my invention.

50. Having thus described my invention, what I claim, and desire to secure by Letters Patent of the United States, is—

1. In a railroad switch, the combination with the switch-stand of a disk pivoted thereon, a weighted switch lever rigidly attached to said disk and connecting rods S' and S^2 , sliding bolt s' and spring s interposed between said rods, the said rods, bolt, and spring, connecting the said disk to the switch 55 points, a dog pivoted in said switch stand and adapted to support said switch and means operated by an approaching train, for tripping said dog and releasing said switch lever, substantially as and for the purposes de- 60 scribed.

2. An apparatus for closing railroad switch-

70. es, comprising a releasing lever pivoted at the requisite distance from the switch and projecting above the ground alongside of the track, a weighted switch lever, a yielding connection between said switch lever and the switch points, a pivoted dog supporting the said switch lever, when the switch is open, a system of rods connecting said releasing lever with said pivoted dog, and a projecting lug or roller attached to the train and adapted to strike said releasing lever and trip said dog, substantially as described.

3. An apparatus for closing railroad switches, comprising a releasing lever pivoted at the 80 requisite distance from the switch and projecting above the ground alongside of the track, means adapted to hold the same normally in a position approximately vertical, a switch stand and a disk pivoted thereon, a 85 weighted switch lever rigidly attached to said disk, a yielding connection between said switch lever and the switch points, a pivoted dog supporting the said switch lever when the switch is open, a system of rods connecting 90 said releasing lever with said pivoted dog, and a projecting lug or roller attached to the train and adapted to strike said releasing lever and trip said dog, substantially as and for the purposes described. 95

4. An apparatus for closing railroad switches, comprising a releasing lever pivoted at the requisite distance from the switch and projecting above the ground alongside of the track, a weighted switch lever, a pivoted dog 100 supporting the said switch lever when the switch is open, a spring normally holding said dog vertical, a system of rods connecting said releasing lever with said pivoted dog, and a projecting lug or roller attached to the train 105 and adapted to strike said releasing lever and trip said dog, substantially as described.

5. An apparatus for closing railroad switches, comprising a releasing lever pivoted at the requisite distance from the switch and projecting above the ground alongside of the track, means adapted to hold the same normally in a position approximately vertical, a weighted switch lever, a pivoted dog supporting the said switch lever when the switch is 115 open, a spring normally holding said dog vertical, a bell-crank lever adapted to trip said dog by hand or foot, a system of rods connecting said releasing lever with said pivoted dog, and a projecting lug or roller attached to the 120 train and adapted to strike said releasing lever and trip said dog, substantially as described.

6. In an apparatus of the character described, the combination with the pivoted 125 switch lever H of the dog N pivoted at n , and provided with eye bolts n' and n^2 , the spring N' normally holding said dog in the position to support the switch lever, and means operated by a moving train to trip said dog and release said switch lever, substantially as and 130 for the purposes described.

7. In an apparatus of the character described, the combination with the pivoted switch lever H of the dog N pivoted at n, and provided with eye bolts n' and n², the spring N' normally holding said dog in the position to support the switch lever, the bell crank lever N² having arm n³ and foot rest n⁴ for tripping said dog, and means operated by a moving train to trip said dog and release said

switch lever, substantially as and for the purposes described.

In testimony whereof I affix my signature in presence of two witnesses.

JAMES A. THATCHER.
